UNITED STATES PATENT OFFICE

GUY L. BONHAM, OF WEST HARTFORD, CONNECTICUT

GAME

Application filed September 17, 1928. Serial No. 306,299.

This invention relates to a game of the ten pin type, one of the objects being to provide a game utilizing a suspended ball adapted to be swung by the player so as to strike the pins 5 on the return or back swing whereby the various shots are rendered quite difficult.

A further object is to provide a game wherein the head pin is located away from the player where it can be among the first 10 struck by the ball during its return movement.

Another object is to so mount the ball that it can be given a spinning movement while swinging, thereby to cause the ball to move in 15 a desired direction both while swinging freely and while contacting with the pins.

A still further object is to provide a game in which the spotted pins are grouped off center relative to the vertical axis about 20 which the ball is adapted to move so that, during the forward swinging movement of the ball it can travel clear of the pins.

A still further object is to provide a game of this type which can be made on a small 25 scale for indoor use and on a large scale for outdoor use, it being unnecessary to provide a special base for the apparatus inasmuch as the same can be erected on a table, floor, or on the surface of the ground.

With the foregoing and other objects in view which will appear as the description 30 proceeds the invention resides in the combination and arrangement of parts and in the details of construction hereinafter described 35 and claimed it being understood that changes in the precise embodiment of the invention herein disclosed may be made within the scope of what is claimed without departing from the spirit of the invention.

In the accompanying drawings the preferred form of the invention has been shown.

In said drawings,

Figure 1 is a side elevation of the game apparatus, the near side of the supporting frame being removed and the extreme positions of the ball being indicated by broken lines.

Figure 2 is a front elevation of the apparatus as viewed from that end where the 50 player stands.

Figure 3 is a top plan view of the pin supporting base showing the normal position of the ball relative thereto, the supporting cord being in section and the pins being properly arranged on the base.

Figure 4 is an enlarged section showing the upper ball supporting coupling.

Figure 5 is a section through the ball showing the connection between said ball and the support.

Referring to the figures by characters of reference 1 designates a railing supported by standards 2 which, in games of small sizes, can be mounted on tables or similar structures in which event the bases 3 of the standards can be provided with soft pads of felt or the like, not shown, so as to prevent injury to the surface on which the game is mounted. In larger structures, however, the standards can be embedded in the ground 50 or can be otherwise held securely in place. It is preferred to provide upper and lower rails at the sides and far end of the structure and a single rail at the front end, this single rail being indicated at 4. The standards and the rails can be made of pipe or the like and extended upwardly from the side rails 55 is a super-structure consisting of upwardly converging frame members 5 connected, at the top, by coupling members 6. These 60 members 5 preferably extend from the side and far end portions of the railings and are so shaped as to afford sufficient clearance to permit the free swinging of the ball used in 65 playing the game.

Depending from the coupling 6 is a tongue 7 having an opening 8 therethrough and the bottom wall of this opening is recessed 70 as indicated at 9. Mounted to rock freely in any direction within this recess is a pointed stud or tooth 10 extending downwardly from a link 11 which extends loosely through the opening 8 and has opposed portions converging downwardly where the link is attached 75 securely to the upper end of a flexible supporting element such as a cord 12. The lower end of this flexible supporting element is attached to an eye 13 located at the upper end of a stem 14 extending diametrically through 80 and rotatable freely within a ball 15. Stem 100

14 is provided at its ends with ball bearings 16 housed within the ball. Thus a swivel connection is provided and the ball is free to rotate readily on the stem.

5 The pins 17 which can be of the same type and number as ten pins, are adapted to be arranged in properly spaced relation upon a triangular base 18 and this base is located to one side of a vertical line extending downwardly from the recess 9 so that under normal conditions the ball 15 will be suspended substantially in position relative to the pins as indicated in Figure 3.

If the game is of small type such as adapted to be used on a table or the like the bottom of the base can be provided with a soft protecting material such as felt or the like so that the base will not scratch the surface on which it is mounted. In a small size game 20 the pins 17 will of course be smaller than in a larger game apparatus for outdoor use which will use pins of standard sizes. A net 19 or other suitable protecting device is adapted to be suspended from the railing 4 where it will be directly in front of the 25 player so as to act as a backstop for the pin when driven backwardly by the ball.

In using this game apparatus the base 18 is properly placed and the pins 17 are properly 30 set up thereon. The player then stands back of the apparatus adjacent the backstop 19 and holds the ball 15 in such position that, when released, it will swing past the pins without touching them and will describe a 35 curve at the far limits of its movement. The ball will then swing back toward the player and, if properly delivered, will strike one or more of the pins so as to knock them from their positions. Obviously extreme skill 40 must be utilized to so regulate the length of the swing, the curvature, and the angle of movement, as to cause the ball to knock down the greatest possible number of pins at one stroke. The counting can be the same as that 45 in ten pins and it will be found that, by twirling the ball about the bearings 16, many intricate plays can be made.

When the pins are struck they will be knocked toward the player who, upon the 50 completion of his play, can readily reach the pins and set them up in their proper positions without requiring the services of a pin boy.

Importance is attached to the fact that the various parts of the apparatus can be separated readily so that said apparatus can be quickly knocked down and stored and as quickly set up for use. Thus while it is especially useful, in small sizes, for use in homes, it can be used, on a larger scale, in 55 club rooms, on fair grounds, and the like.

What is claimed is:

A game apparatus including connected rails and frame members providing an enclosure, a tongue supported by the frame members above the enclosure and provided with

an opening having a bottom recess, a link extending loosely through the opening and downwardly from the tongue, a tooth within the link and bearing in the recess for holding all portions of the link normally spaced from the tongue, a flexible supporting element depending from the link, a ball, a stem on which the ball is mounted for rotation, means for connecting the stem to said flexible connection, and game pieces in the enclosure adapted to be struck by the ball. 75

In testimony that I claim the foregoing as my own, I have hereto affixed my signature.

GUY L. BONHAM.
